UNITED STATES PATENT OFFICE.

PHILIP MUELLER, OF DECATUR, AND ANTON C. SCHUERMANN, DECEASED, LATE OF DECATUR, ILLINOIS, BY HELENA SCHUERMANN, EXECUTRIX, OF DECATUR, ILLINOIS, ASSIGNORS TO ADOLPH MUELLER, TRUSTEE, OF DECATUR, ILLINOIS.

PIPE-BENDING MANDREL.

Application filed October 17, 1925. Serial No. 63,188.

The present invention relates to improvements in mandrels employed for bending tubes or pipes, and particularly to that type of mandrel which includes a flexible section 5 adapted to be inserted in a tube and bent therewith about a suitable axis.

The particular object of the invention is to provide a mandrel of the type or character referred to in which there will be provided a continuously smooth surface that will contact with the inner face of the tube wall during the bending operation. With this end in view, the improved mandrel includes a plurality of superposed thin, strips 15 of resilient material providing an exterior smooth surface throughout substantially the entire length of the flexible mandrel section, which surface will contact with the inner face of the tube wall and prevent distortion 20 of such wall during the bending operation.

In the accompanying drawings:

Fig. 1 is an elevation of one embodiment of the invention, the supporting stem or rod and an adjustable sleeve being shown in section.

Fig. 2 is a transverse section on the line 2-2 of Fig. 1.

Fig. 3 is an elevation, partly in section, of a slightly modified form.

Fig. 4 is a transverse section on the line 4-4 of Fig. 3.

Fig. 5 is a transverse section of another form.

Referring particularly to Figs. 1 and 2, the improved mandrel comprises a rigid rod or stem 1 which is provided, at one end, with a suitable socket in which are secured a series of superposed elongated resilient metal strips 3. The strips 3 are of such form 35 that, collectively, they provide a body of circular form in cross section, as shown in Fig. 2, and having a continuously smooth exterior surface which comes into contact with the interior of the tube to be bent. As 40 shown, the strips are of different lengths and so arranged that the free end of the mandrel section formed thereby is tapering or inclined.

By employing a mandrel of the character 50 shown in Figs. 1 and 2, it is possible to bend a tube without causing any distortion of the wall thereof, and thereby avoid the

necessity for employing, at the free end of the mandrel, a sizing head, such as is commonly required to restore the desired cross 55 sectional form of the tube as the mandrel is withdrawn after the bending operation.

As repeated bendings of the flexible body may tend to cause the several resilient strips to separate slightly, it is preferred to surround such strips with a sleeve 4. This sleeve embraces the series of strips sufficiently close to retain them in the desired cylindrical form, and is adapted to be manually reciprocated over said strips to restore them 60 to the original, desired, position in case any such separation, as is above referred to, may have taken place. The length of the sleeve is, of course, relatively slight, and it is positioned adjacent the rod or stem 1 when the 65 flexible section of the mandrel is inserted in a tube.

Instead of forming the flexible section solely from thin resilient strips, as shown in Figs. 1 and 2, it is possible to obtain 70 the advantages of having a continuously smooth surface for contact with the interior of the tube to be bent by providing two series of such strips at diametrically opposite points of a suitable flexible core. Such 75 an arrangement is illustrated in Figs. 3, 4 and 5.

Referring to Fig. 3, the rod or stem 1 of the mandrel is connected to one end of a flexible body which comprises a series of 80 pivotally connected core members 5 which are surrounded by and pivotally connected with sections 6 of the cross sectional form shown in Figs. 4 and 5. As shown, each tubular member 6 has oppositely arranged 85 circular portions which are connected by diametrically opposite flat surfaces 7, 8, and against each of such flat surfaces is arranged a plurality of thin resilient metal strips 9 which extend into suitable recesses in the 90 stem or rod 1, and are rigidly secured thereto.

The several core sections 5 are interengaged by suitable tongues and recesses, and also pivotally connected by transverse pivot 100 pins 10. The tubular body members 6 are in turn pivotally connected by pivots 11 to the core members, and in elevation, said members 6 are given such a form as permits

relative lateral movement between them, so that the mandrel may readily bend with the tube surrounding it.

The thin resilient strips 9 are of different lengths, as in the embodiment of the invention illustrated in Fig. 1, and said strips are not rigidly connected with the other parts of the mandrel, except by the screws 12, so that they are capable of relative longitudinal movement during the bending operation.

At the terminal end of the core, there is arranged a sizing head 14 which, as usual, will have the cross sectional form and be of the same dimensions as the bore of the tube to be bent. The number of strips 9 may be such as to make the flexible section of the mandrel circular in cross section substantially throughout its length, as shown in Fig. 5, or, if preferred, the number of such strips in one of the groups may be slightly less than that in the other, so that there will be provided a substantially flat surface 15 throughout the length of the flexible section which will allow slight collapsing of the wall of the tube being bent and reduce the amount of friction between the mandrel and tube during the bending operation. As the mandrel is withdrawn from the bent tube, the head 14 will act to restore to the desired circular, cross sectional, form any portion of the tube which may have collapsed against the surface 15. It is preferred to employ a sleeve 4 which can be reciprocated over the flexible section of the mandrel in the form of the invention shown in Fig. 3, as well as that shown in Fig. 1, said sleeve acting, as before described, to radially compress the resilient strips and maintain them in close contact, in case, after repeated operations, there is a tendency for them to separate or become radially spaced at the free ends.

It is believed that the method of using and advantages of the construction hereinbefore described will be readily apparent from the description and the drawings, and it is to be understood, of course, that, except where specifically set forth in the accompanying claims, the invention is not intended to be limited to the exact details shown.

Having thus described the invention, what is claimed is:

1. A tube bending mandrel comprising a flexible body including a series of superposed, thin, strips of resilient material, a stem to which all of said strips are secured adjacent one end, and a sleeve closely surrounding the flexible body and movable longitudinally thereof.

2. A tube bending mandrel comprising a flexible body, substantially cylindrical in cross section and including a series of superposed, thin, strips of resilient material, and a stem to which all of said strips are se-

cured adjacent one end, the strips being of different lengths and arranged so that the free ends thereof extend successively greater distances from the stem.

3. A tube bending mandrel comprising a flexible body including a series of superposed, thin, strips of resilient material, a stem to which all of said strips are secured adjacent one end, said strips being of different lengths and arranged so that the free ends thereof extend successively greater distances from the stem, and a sleeve closely surrounding the flexible body and movable longitudinally thereof.

4. A tube bending mandrel comprising a core formed by a plurality of pivotally connected members, a stem, and a thin strip of resilient material connected at one end to the stem and extending longitudinally of the core to form a smooth unbroken surface over the joints between the members of the core.

5. A tube bending mandrel comprising a core formed by a plurality of pivotally connected members, a stem, and thin strips of resilient material connected at one end to the stem and extending longitudinally of the core to provide two diametrically opposite, smooth surfaces over the joints between the members of the core.

6. A tube bending mandrel comprising a core formed of a plurality of pivotally connected members, a stem, and two sets of thin strips of resilient material attached to the stem and extending across joints between the members of the core at diametrically opposite points, each said set including a plurality of superposed strips.

7. A tube bending mandrel comprising a core formed of a plurality of pivotally connected members, each being of substantially circular form in cross section with diametrically opposite, parallel truncated surfaces, a stem, and a plurality of superposed thin strips of resilient material attached to the stem at one end and extending over the truncated portions of the core members and across the joints between said members.

8. A tube bending mandrel comprising a core formed of a plurality of pivotally connected members, a stem attached to one end of the core, a head connected to the other end of the core, and a plurality of thin strips of resilient material secured at one end to the stem and extending therefrom over the core, to form smooth surfaces across joints between the core members, toward the head.

9. A tube bending mandrel comprising a core formed of a plurality of pivotally connected members, a stem attached to one end of the core, a head connected to the other end of the core, a plurality of thin strips of resilient material secured at one end to the

stem and extending therefrom over the core, to form smooth surfaces across joints between the core members, toward the head, and a sleeve embracing said strips and core and movable longitudinally thereof.

10. A tube bending mandrel comprising a flexible body including a series of superimposed thin strips of resilient material connected together adjacent one end, and means adjustable longitudinally of the mandrel for exerting pressure on said strips of resilient material to maintain contact between disconnected portions of such strips, for the purpose described.

15. 11. A tube bending mandrel comprising a flexible body including a series of superim-

posed, thin, strips of material connected together at one end, and a sleeve closely surrounding said body and movable longitudinally thereof, said sleeve being normally positioned near the connected ends of the resilient strips.

In testimony whereof, we, PHILIP MUELLER, and HELENA SCHUERMANN, executrix of the last will and testament of ANTON C. SCHUERMANN, deceased, have hereunto set our hands.

PHILIP MUELLER.
HELENA SCHUERMANN,
Executrix of Anton C. Schuermann, Deceased.
